UNITED STATES PATENT OFFICE.

ALFRED C. GALDI AND ARMAND GALDI, OF SOMERVILLE, MASSACHUSETTS.

WINE PRESS.

1,412,029.

Specification of Letters Patent. Patented Apr. 4, 1922.

Application filed December 3, 1920. Serial No. 428,025.

To all whom it may concern:

Be it known that we, ALFRED C. GALDI and ARMAND GALDI, citizens of the United States, residing at Somerville, in the county of Middlesex, in the State of Massachusetts, have invented a certain new and useful Improvement in Wine Presses, of which the following is a specification, reference being had to the accompanying drawings.

10 This invention relates to manually operated presses for use in the making of wine, cider and the like, and our immediate object is to provide, at a reasonable cost, a portable press which is specially suited for family 15 use and in which the mechanical construction is such that great power may be produced by a single operator during the act of compressing the fruit. A further improvement consists of special means whereby the jacket 20 which encloses the said fruit may be readily removed from its operative position in order that the so called "cheese" or pummice may be removed from the press. Other advantages of improvement will be specifically 25 described and claimed hereinafter.

In order to explain our invention clearly we have provided the annexed drawings, in which the Figure 1 is an elevation of a press embodying our present improvements and 30 Figure 2 is a top or plan view of the same. Figure 3 is a detail view of one of the clamps by means of which the two part jacket which surrounds the press proper is latched together. Figure 4 is an elevation of the press 35 stripped of its cylindrical jackets, showing particularly the manner of removing the two part press-board 22. Figure 5 is a vertical, central, sectional, view of the base plate 10. Figure 6 is mainly an elevation of certain 40 lever-operated mechanism by means of which increased pressure may be given to the press-boards 22 after the initial pressure has been given through the screw 19, nut 21 and hand wheel 20. Figure 7 is a plan view of the 45 mechanism shown in said Figure 6 and Figure 8 is a detail, side, view of said mechanism.

In these drawings the numeral 10 indicates a substantial base-plate which is here 50 shown as mounted on a plurality of legs 11.

Removably mounted on said base-plate is an outer jacket 12, of sheet material, which serves to prevent the fruit juices from squirting laterally while the said fruit is being 55 placed under pressure and located within, and concentric with, said outer jacket 12, is a

two-part wall formed of vertical strips 13 which are suitably spaced apart and are connected by hoops 14, the meeting ends of said hoops being connected by clamps that are 60 best seen in Figure 3 of the drawings. Each clamp consists essentially of a lug 15 on one of the hoop members 14 and of a latch 16 that is hinged at 16^a to the opposing end portion of the companion hoop member and 65 is adapted to be latched over the lug 15, as will be best understood by reference to Figures 2 and 3 of the drawings. Formed in the base plate 10, between the outer shell 12 and the slotted shell 13 is a groove 17 which 70 is provided to receive the fruit juices and to convey the same to a discharge spout 18. Rotatably mounted in the central portion of base plate 10 is a screw 19 which has fixed to its upper end a hand wheel 20 and on its 75 mid portion a threaded plate 21 and located below said threaded plate is a two-part pressure board 22 which rests upon the cheese of fruit when the press is in operation.

When it is desired to use the described 80 press the outer shell 12 and slotted jacket 13 are mounted on the base plate 10 and the screw 19 is suitably rotated to raise the plate 21 above the level of the tops of the slots 13. The fruit is then poured into the 85 basket formed by the slotted jacket, the two-part pressure board 22 is placed on said fruit, the hand wheel 20 is suitably rotated to run the threaded plate 21 down upon the pressure board 22. Continued rotation of 90 the screw 19 then operates to compress the fruit until the juices are forced outward between the slots 13 and run down by gravity into the trough 17 and are discharged thence through the spout 18 into a suitable receptacle. 95

After the juices have been thus pressed out of the fruit the outer jacket 12 is removed and the two parts of the jacket 13 are disconnected by unlatching the latches 16, when 100 the two parts may be removed from the base-plate. The cheese or pummice may then be readily removed from the press.

In order that extraordinary power may be applied to screw 19 we have provided supplemental mechanism which is best seen in Figures 6, 7 and 8 of the drawings, which we will now describe. Secured to the lower end of the screw 19 is a ratchet wheel or gear 23 which is engaged by a double-end pawl 24 105 which is pivoted, at 25, in a lever 26 that is fulcrumed at 27 in an extension 28 of the

base plate 10. The numeral 29 denotes an upright lever which is fulcrumed at 30, on the extension 28; the lower end portion of the lever 29 being connected with the outer end of the lever 24 in such manner that, when the upper end of the lever 29 is reciprocated, the lever 26 will be rocked on its fulcrum 25 and the pawl 24 will operate, through the medium of ratchet disc 23, to 10 rotate the screw 19 with a step-by-step movement. We are thus enabled to apply extraordinary pressure to the press-board 22, if desired, after the screw has been manually rotated by means of the hand wheel 20. 15 Our described invention provides, at a reasonable cost of construction, a press which is specially convenient for family use, which is effective in its operation and results, and which may be readily taken apart for the 20 removal of the pumice and for cleaning.

Having thus described our invention, we claim:—

1. In a press of the class referred to, a circumferentially grooved base, a screw centrally and rotatably mounted in said base, an outer shell and an inner slotted two-part jacket mounted on said base, a hand wheel fixed on said screw, and means for latching the two parts of said jacket together. 25

2. In a press of the class referred to, a circumferentially grooved base, a screw centrally and rotatably mounted on said base, an outer shell and an inner slotted two part jacket mounted on said base, a hand wheel fixed on said screw, means for latching the 30 two parts of said jacket together, and supplemental means for rotating said screw. 35
